UNITED STATES PATENT OFFICE

2,086,011

STENCIL AND INKING DEVICE THEREFOR

William B. Whitmore, Chicago, Ill., assignor to
Ditto, Incorporated, a corporation of West Vir-
ginia

Original application March 30, 1933, Serial No.
663,581. Divided and this application August
16, 1935, Serial No. 36,568

3 Claims. (Cl. 41—31.6)

The invention relates to stencils and inking devices therefor and is particularly adapted to be embodied in stencils of the type commonly employed in mimeographing machines.

5 In accordance with the invention, I provide an improved stencil comprising in combination therewith, an inking or color containing means and a moistening means containing a solvent for the ink or color in said inking or color containing means. Thus, the novel combination may comprise a stencil having an impression surface and a backing of a material capable of passing ink or colors in solution, an inking or color containing means in back thereof and having an ink or dye thereon or therein, and a moistening means in contact with said inking means whereby the solvent from the moistening means will pass by capillarity through the inking means to form a solution of the ink or color, which solution will in 10 turn pass by capillarity through the stencil and to the impression surface thereof.

This invention has other advantages which will become apparent as the following detailed description progresses, reference being had to the 25 accompanying drawing which is a fragmentary section taken through a stencil, improved means for inking the stencil and means for moistening the inking means.

This application is a division of my co-pending 30 application, Serial No. 663,581, filed March 30, 1933 Patent No. 2,012,526, August 27, 1935.

The stencil 20 designates generally a stencil of the conventional type. The stencil 20 preferably comprises a sheet of paper 21 provided with the 35 usual coating 22 which may be a lacquer having a cellulose base. The paper backing may be suitably formed of any of the known suitable porous papers that will permit the passage of liquids therethrough by capillarity and is for example 40 preferably yoshino paper. The reference character 25 designates an inking device or color carrier which comprises a sheet of paper 12b, similar to the paper backing 21. One surface of the paper 12b is provided with a coating 14b which 45 comprises a dye, color or ink preferably soluble in water, although other dyes and inks as for example the water insoluble dyes or inks may be used and subjected to suitable solvents therefor during the duplicating operation. As a suitable 50 ink, for example, water or alcohol soluble dyes such as crystal violet or methyl violet may be employed, incorporated in the desired vehicle. The requirements of the vehicle are that it will bind the dye or pigment to the paper and will 55 not prevent solution of the dye when the solvent is brought into contact therewith. As an example of a suitable vehicle for use with water as the solvent, gum arabic and glycerine may be used.

In the drawing, the inking device 25 is shown

interposed between the stencil 20 and a moistening means 11b which may be, for example, preferably a hectograph band comprising a paper backing 15b having a coating 16b of gelatin. The moistening means 11b may comprise a layer 5 of cloth, felt, gelatinized material or in fact any other material capable of storing and delivering a supply of solvent or capable of transmitting the solvent from a reservoir to the stencil. However, in this instance I have shown a duplicating band 10 of the type employed in hectograph machines.

The data to be duplicated are cut into the coating 22 as indicated at 18b.

When the inking device 25 is to be employed in a duplicating operation, the stencil 20 is placed 15 upon the coating 14b and the inking device 25 is placed upon the gelatin coating 16b in the manner illustrated in the drawing, the gelatin coating 16b having first been thoroughly moistened. Water from the gelatin passes upwardly by capillarity 20 through the paper 12b and dissolves the ink or dye in the coating 14b to form a solution of the ink or dye. This solution then passes by capillarity up through the paper 21 into the openings made for the data 18b. The sheets to be duplicated 25 are placed upon the coating 22 and sufficient pressure is applied to the sheets so that the data will be duplicated thereon.

I claim:

1. In combination with a stencil, an inking 30 device comprising a paper, and a coating including an inking substance applied to a surface of the paper, said inking substance being adapted to be released upon application of a solvent thereto whereby the inking substance is carried to the 35 impression surface of the stencil.

2. In combination, a stencil, a sheet inking 40 device carrying a dry dye or ink in back thereof and moistening means in contact with said inking device, said moistening means containing a solvent adapted to pass by capillarity through the inking device and stencil and carry with it the ink contained in the inking device to deposit it at the impression surface of the stencil.

3. A composite structure for use in a duplicating process comprising a stencil having an impression surface and a porous backing, a solvent storage means capable of transmitting the solvent to the stencil and an intermediate inking device comprising a porous backing in contact with said means and a coating of a color on said backing in contact with the stencil backing whereby the solvent will pass by capillarity through the inking device to form a solution of the color thereupon and the solution of color will pass by capillarity 55 through the stencil to the impression surface thereof.

WILLIAM B. WHITMORE.
